GAME

Edward G. Perrier, Hunters Point, Quebec,
Canada

Application October 31, 1938, Serial No. 238,052

1 Claim. (Cl. 273—99)

This invention relates to a game to provide amusement. The game may be said to be a game of skill wherein one may become proficient after much practice.

A further object of the invention is to provide a game having all the movable discs attached to a main element thereby preventing loss of the various parts when playing the game.

Another object of the invention is to provide a game of extreme simplicity and inexpensive construction.

With these and other objects in view that may appear while the description proceeds the invention consists in the novel construction and arrangement of parts as hereinafter more specifically set forth, claimed and shown in the accompanying drawing forming part of this application and in which:

Fig. 1 is an assembly view of the game apparatus.

Fig. 2 is a view showing the various elements of the game.

Fig. 3 is a detailed view showing the main element in section.

Referring more in detail to the drawing in which similar reference characters designate corresponding parts throughout the several views it will be seen the invention consists of a pin 10 of wood, Celluloid or other suitable material. Said pin is preferably circular in cross-section and pointed at the end 11. The end 12 is provided with an aperture 13 and a cord 14 is tied on the same.

A plurality of circular discs 15 are provided each being of slightly smaller diameter than the preceding disc and arranged with a bevelled edge 16 in a manner to form a partial cone when the same are together as in Fig. 1. The discs are constructed with concentrical apertures 17 there-

in through which the cord 14 is threaded and is tied to a smaller disc 18 to keep the remainder on the cord.

The game is played by grasping the pin 10 in one hand and swinging the cord 14 carrying the discs 15 loosely thereon. While the discs are in midair the first one is speared with the pin 10, an attempt being made to insert the point of the pin into the aperture of the disc. Each succeeding disc is treated in a similar manner until the entire set have been caught on the pin.

From the foregoing it will be seen I have provided a game which is novel in construction and application and will prove amusing for young or old alike.

It is believed that the construction and advantages of the structure shown may be apparent from the foregoing paragraphs taken in conjunction with the accompanying drawing without further detailed description.

While the preferred embodiment of the invention has been disclosed it is understood that minor changes in the details of construction, combination and arrangement of co-operating parts may be resorted to within the scope of what is claimed without departing from the spirit of the invention.

I claim:

In a game as described comprising a pin having a pointed end, a cord having one end fixedly attached to the opposite end of said pin, a plurality of apertured discs loosely mounted on said cord, each succeeding disc having its inner and outer peripheries of less diameter than the preceding disc, and means on the free end of said cord for retaining the discs thereon whereby the discs may be thrown into the air and caught by the pin.

EDWARD G. PERRIER.
